UNITED STATES PATENT OFFICE.

KARL KIEFER, OF CINCINNATI, OHIO.

VACUUM TRAP.

Application filed June 14, 1920. Serial No. 388,867.

To all whom it may concern:

Be it known that I, KARL KIEFER, a citizen of the United States, and a resident of Cincinnati, in the county of Hamilton and State of Ohio, have invented certain new and useful Improvements in Vacuum Traps, of which the following is a specification.

My invention relates to an apparatus designed for the automatic removal of a liquid that accumulates in a closed system of vessels or pipes in which a sub-atmospheric pressure is maintained.

In the accompanying drawing the apparatus is shown in cross section and consists of a vessel divided into two compartments, an upper compartment A and a lower compartment B. In the drawing the two vessels are represented as having cylindrical glass walls a' and b' . C is the cover of the upper vessel, D is an intermediate wall between the two vessels, and E is the bottom of the apparatus.

Rubber gaskets are placed on all edges 25 of the glass cylinders, and a series of draw bolts F and F' are used to hold the two vessels together and make them air and liquid tight by forcing bottom and top against the glass cylinders.

The top C has apertures G and H, the latter leading to the exhaust pump and G connected with the system from which liquid is to be continuously removed. However, instead of leading to an exhaust pump, 35 H could be connected to an upper part of the system of vessels or pipes in which is maintained a sub-atmospheric pressure.

The separating wall D carries in its center two valves K and L operating in respective bores. The bodies of both K and L are fluted so as to permit air to pass by and allow free movement within the bores. The bore in which the valve K operates is closed on the top by means of a plug 2. 45 The valve part proper of the valve K is on its lower end and it can open or close the small opening 3, giving access of the lower valve chamber B by means of a bore O in the intermediate wall D to the exterior atmosphere. This is the position shown in the drawing where the valve K has been lifted by means of a disc shaped projection T carried by a float M. This projection T is engaged by stop 5, to prevent the float 55 from falling too far downward when there is no liquid in chamber B.

Float M is directly connected to the valve L. The valve proper of L is at its upper end and can open and close opening 4, giving access of air in the upper part of chamber B to the upper part of chamber A by means of tube N. In the position shown this opening 4 is closed as the float M is raised by the liquid which it is shown as having accumulated in the lower chamber B.

In the separating wall D is another aperture P extending into the lower chamber B and carrying at its lowest end a check valve Q. This check valve is so constructed that liquid can descend from chamber A to chamber B, but it cannot ascend therein.

A similar tube R is fastened in the bottom E of the lower chamber, and a check valve S is provided which will allow the descent of liquid in chamber B to the atmosphere, but will close itself as soon as the sub-atmospheric pressure is produced within chamber B.

Chamber A being connected by intake G with a system of pipes or vessels under sub-atmospheric pressure, it therefore always shows the same sub-atmospheric pressure. If any liquid accumulates in the system of pipes or vessels it will flow through the intake G into the chamber A.

If we suppose now that the valve L is open and the valve K is closed (which is the opposite position from that shown in the drawing), then it will be seen that the same sub-atmospheric pressure will prevail in 90 the chamber B as in chamber A because there is a communication and an exchange of pressures by means of tube N and valve opening 4. Valve K shuts off the chamber B from the atmosphere by closing the passage O. Both chambers A and B being now of sub-atmospheric pressure, the liquid that accumulates in A will descend into the lower chamber by gravity through the aperture P, opening the check valve Q and rise 100 in the lower chamber.

In consequence thereof the float M will rise and by its increasing buoyancy will finally overcome the atmospheric pressure upon the valve K and open same by means of projection T, at the same time raising valve L and closing opening 4. This action interrupts the connection between the chambers A and B and opens the lower chamber B through the passage O to the atmosphere. Air will rush into the chamber B 110 until an atmospheric pressure is established

therein whereupon the liquid in B will descend through the aperture R and check valve S into the open. The liquid will flow out until it cannot carry any longer the float 5 M in its high position, whereupon float M drops, reversing again the two valves, repeating this operation as long as there is any liquid coming from the system of pipes or vessels to be drained by the apparatus 10 shown.

It is important that the valves should be opened and closed quickly. The rise and fall of the float M should not therefore be a gradual one, so that it may not, for instance, 15 stay in a neutral position whereby both valves are open. This is easily attained by proportioning the area of the valves so that not only the weight of the valves themselves has to be overcome, but also the atmospheric 20 and sub-atmospheric pressure pressing upon these valves.

It is well known that valves of the form shown herein require a certain pressure to lift from their seats, but after being lifted 25 therefrom it takes very little effort to hold them within the neighborhood of their seats. If the buoyancy of the float M be sufficient to overcome the atmospheric pressure upon valve K besides its own weight, and the 30 weight of the float must be sufficient to overcome the sub-atmospheric pressure exerted upon valve L when the liquid sinks in the chamber B, either valve will completely open suddenly after having been retarded 35 in its closed position by the excess of pressure on one side, and the other valve will be allowed to close at the same time. The area of these valves, therefore, depends somewhat upon the degree of vacuum that is 40 maintained in chamber A. This area must be smaller for greater vacuum and enlarged for low degree of vacuum. This dispenses with springs or the like to effect quick complete closure or opening of either valve K or 45 L.

Having described my invention, what I claim and desire to secure by Letters Patent is:

1. In a vacuum trap, the combination of 50 a chamber always under sub-atmospheric pressure, with a chamber alternately under sub-atmospheric and atmospheric pressure, said chambers having a single separating wall, and means entirely within said chambers, mounted in said wall, for transferring liquid accumulating in the first mentioned chamber to the atmosphere.

2. A vacuum trap having a constantly 55 sub-atmospheric chamber and an intermittently sub-atmospheric chamber with a passage from one chamber to the other, a float in one chamber, and a valve to control said passage, pneumatically retarded for sudden opening by the weight of said float.

3. A vacuum trap having a constantly

sub-atmospheric chamber and an intermittently sub-atmospheric chamber with a passage from one chamber to the other, a rectilinearly guided float in one chamber, and a rectilinearly guided valve entirely within 70 said chambers, unitary with and operated by said float.

4. A vacuum trap having a constantly sub-atmospheric chamber and an intermittently sub-atmospheric chamber with a passage from one chamber to the other, a float in one chamber, and a valve to control said passage, entirely within said chambers, pneumatically retarded for sudden opening 75 by the weight of said float.

5. A vacuum trap having a constantly sub-atmospheric chamber and an intermittently sub-atmospheric chamber, this latter chamber having an atmospheric passage and having a sub-atmospheric passage from one 85 chamber to the other, a float, and valves alternately closed and opened by said float for controlling the respective passages, said valves having their weights and areas so proportioned to said float and to the constant pressure reduction that they are completely opened by said float suddenly after being retarded by pneumatic pressure.

6. A vacuum trap having a constantly sub-atmospheric chamber and an intermittently sub-atmospheric chamber with a single wall between them, this latter chamber having an atmospheric passage and having a sub-atmospheric passage from one chamber to the other through said wall, a float, 100 and valves entirely within said chambers, mounted in said wall, alternately closed and opened by said float for controlling the respective passages.

7. A vacuum trap having a constantly 105 sub-atmospheric chamber and an intermittently sub-atmospheric chamber, this latter chamber having an atmospheric passage and having a sub-atmospheric passage from one chamber to the other, a float, and valves 110 entirely within said chambers, alternately closed and opened by said float for controlling the respective passages, said valves having their weights and areas so proportioned to said float and to the constant pressure reduction that they are completely opened suddenly by said float after being retarded by pneumatic pressure.

8. A vacuum trap having an upper chamber, and having a lower chamber with a liquid passage and an air passage from one chamber to the other, a float in said lower chamber, and a valve controlling said air passage, said valve having its weight and area so proportioned to said float and to the pressure in one of said chambers and being so related to said float that it is completely opened by said float suddenly after being retarded by pneumatic pressure.

9. A vacuum trap having an upper chamber

- ber and a lower chamber with a liquid passage and an air passage from one chamber to the other, entirely within said chambers, and a float in said lower chamber controlling said air passage.
10. A vacuum trap comprising a chamber alternately under atmospheric pressure and sub-atmospheric pressure, having a submerged valve opening to admit liquid and an opening to discharge liquid.
11. A vacuum trap having an upper chamber and a lower chamber, said lower chamber having an atmospheric passage and having a sub-atmospheric passage from one chamber to the other, a vertically sliding float, and vertically sliding valves, one unitary with said float and the other engaged by said float, whereby said valves are operated by said float to control the respective passages.
12. A vacuum trap comprising a receptacle with a chamber continuously closed to the atmosphere and open to pressure-reducing means, and automatically actuated discharge means mounted entirely on one inclosing part of said chamber and entirely within said receptacle, for discharging liquid from said chamber without materially affecting the constantly reduced pressure condition in said chamber.
13. A vacuum trap comprising a receptacle with a chamber continuously closed to the atmosphere and open to pressure-reducing means, and liquid-controlled means mounted entirely on one inclosing part of said chamber and entirely within said receptacle, for discharging liquid from said chamber without materially affecting the constantly reduced pressure condition in said chamber.
14. A vacuum trap comprising a two-chambered receptacle with a partition between the chambers having an opening from one chamber to the other, a pressure-reducing connection to one of said chambers, closed off from the other chamber except through said one chamber, a valve mounted entirely on said partition and entirely within said receptacle for controlling said opening, and a float in one of said chambers, mounted entirely on said valve, for controlling said valve for discharge of liquid from said chambers without materially affecting the constantly reduced pressure condition in said one chamber.
15. A vacuum trap comprising a two-chambered receptacle with an opening from one chamber to the other, a pressure-reducing connection to one of said chambers, closed off from the other chamber except through said one chamber, a float in one of said chambers, and a valve completely opened suddenly by said float, after being retarded in closing position by pneumatic pressure, for discharging liquid from said
- chambers without materially affecting the constantly reduced pressure condition in said one chamber.
16. A vacuum trap comprising a receptacle with a chamber continuously closed to the atmosphere and open to pressure-reducing means, and automatically and suddenly entirely rectilinearly actuated discharge means entirely within said receptacle for discharging liquid from said chamber without materially affecting the constantly reduced pressure condition in said chamber.
17. A vacuum trap comprising a receptacle with a chamber continuously closed to the atmosphere and open to pressure-reducing means, and means pneumatically retarded from a movement to discharge liquid from said chamber and having said movement suddenly completed by gravity, to discharge said liquid without materially affecting the constantly reduced pressure condition in said chamber.
18. A vacuum trap comprising a partition separating two chambers therein, one chamber having a pressure-reducing connection and the other chamber having a liquid-outlet, said partition having a liquid passage and an air passage from one chamber to the other, and having an interior space closed off from the one chamber and a port from this space to the exterior of the trap, this space having a passage into said other chamber, a valve controlling this passage and opening away from this other chamber, a valve controlling said air passage between the two chambers and opening inwardly toward this other chamber, and a float in this other chamber alternately opening these valves.
19. A vacuum trap comprising a partition separating two chambers therein, one chamber having a pressure-reducing connection and the other chamber having a liquid outlet, said partition having a liquid passage and an air passage from one chamber to the other, and having an interior space closed off from the one chamber and a port from this space to the exterior of the trap, this space having a passage into said other chamber, elongated valve elements sliding lengthwise in said air passage and said interior space, respectively, and opening, respectively, inwardly toward said other chamber and away from this other chamber, each of said valve elements having an extension into this other chamber, and a float in this other chamber, mounted directly on the extension of the valve element that opens away from this chamber and adapted to engage the extension of the other valve element, so that either valve is closed as the other is opened, by alternate movements of said float.
20. A vacuum trap comprising a receptacle with two chambers, vacuum and pres-

- sure connections with the respective chambers, air and liquid connections between the chambers, oppositely opening valves to control said pressure and air connections, respectively, the pressure tending to seat said valves, and liquid-controlled means within said receptacle operatively related to said valves to close either valve while opening the other.
- 10 21. A vacuum trap comprising a receptacle with two chambers, vacuum and pressure connections with the respective chambers, air and liquid connections between the chambers, oppositely opening valves to control said pressure and air connections, respectively, entirely within said receptacle, the pressure tending to seat said valves, and liquid-controlled means within said receptacle operatively related to said valves to close either valve while opening the other.
- 15 22. A vacuum trap comprising a receptacle with two chambers, vacuum and pressure connections with the respective chambers, air and liquid connections between the chambers, oppositely opening valves, having adjacent extensions, said valves controlling said pressure and air connections, respectively, the pressure tending to seat said valves, and liquid controlled means connected to the extension of the air-connection

controlling valve and engaging with or disengaging from the extension of the other valve as the air-connection controlling valve is closed or opened, respectively, to open this other valve or allow it to close.

35

23. A vacuum trap comprising two chambers, one communicating with the other and also with the atmosphere, two oppositely opening valves controlling the communications between the chambers and the atmospheric communication, respectively, said valves being seated by atmospheric pressure, and a float connected to the inter-chamber valve and engageable with or disengageable from the other valve.

40

24. A vacuum trap comprising a partition and having two chambers separated by and immediately adjoining said partition, and means controlling communication between the chambers, mounted entirely on said partition, one of said chambers having a pressure reducing connection closed off from the other chamber except through said one chamber under the control of said controlling means.
